INVENTOR
Alexander Milne
BY
George Cook, Son
ATTORNEYS

UNITED STATES PATENT OFFICE.

ALEXANDER MILNE, OF NEWARK, NEW JERSEY, ASSIGNOR TO NEWARK WATCH CASE MATERIALS COMPANY, OF NEWARK, NEW JERSEY, A CORPORATION OF NEW JERSEY.

WATCH HOLDER.

Application filed January 31, 1921. Serial No. 441,129.

To all whom it may concern:

Be it known that I, ALEXANDER MILNE, a citizen of the United States, and a resident of Newark, in the county of Essex and State 5 of New Jersey, have made and invented certain new and useful Improvements in Watch Holders, of which the following is a specification.

My invention relates to watch holders, 10 and particularly to that class in which they are formed of sheet metal and designed to hold a watch in position either upon a supporting surface, such as the dashboard of an automobile, or to maintain the watch in a 15 slightly tilted position, as upon a desk.

The object of my invention is to provide an improved watch holder or supporting device which is simple in construction and arrangement, may be economically manufactured, and so designed that the watch may 20 be easily and quickly removed from the holder, either for the purpose of convenience in winding or setting, or for the insertion of a new watch.

25 While the holder is particularly adapted for the support or holding of the popular grade of watch (formerly known as the "dollar" watch) it will be readily appreciated that it is adapted to hold any style 30 or type of watch.

A further object is to provide a watch holder formed of two sections which when brought together form a watch receptacle and to provide an efficient clamping device 35 for holding the sections together; thus allowing a watch to be easily and readily inserted in the holder or removed therefrom, and to further provide means whereby the two sections are positively locked in as- 40 sembled positions, and thus prevent the theft of the watch.

With the foregoing and other objects in view, my invention consists in the improved watch holding device illustrated in the accompanying drawing and hereinafter described and claimed, and in such variations and modifications thereof as will be obvious to those skilled in the art to which my invention relates.

50 In the drawing accompanying and forming a part of this specification and wherein the preferred embodiment of my invention is illustrated:

Figure 1 is a view in perspective of my 55 improved watch holder designed and con-

structed for holding a watch upon a desk or other horizontal surface;

Figure 2 is a view in vertical section taken on the line 1—1 of Figure 1;

Figures 3 and 4 are front and rear views 60 respectively of the above-mentioned holder;

Figure 5 is a view in front elevation of a watch holder particularly designed for holding and displaying a watch upon a vertical surface, such as the dashboard of an automobile, the holder being provided with additional means for holding the sections together;

Figure 6 is a view in section taken on the line 6—6 of Figure 5;

Figure 7 is a detail view in section showing the manner in which the clamp is adapted to hold the sections in assembled position; and

Figure 8 is a detail view in section showing the manner in which the sections may be positively locked in assembled position.

Referring specifically to the several views, wherein similar reference numerals designate corresponding parts throughout, the 80 holder as constructed in Figures 1 to 4 inclusive, is formed with the front section 10 and the rear section 11. The front section includes the bezel-engaging ring 12, and the rear section the back plate 13, the two being 85

so curved and proportioned, that when the sections are assembled a watch-receiving receptacle 14 is formed. The front and rear sections are provided with the openings 15, providing for the passage of the stem of 90 the watch therethrough, whereby the watch is held from turning and due provision is made for its winding. The front and rear sections also include the rearwardly extending supporting or spacing walls 16—17, 95 which are preferably conical shape in outline and which are adapted to nest one within the other.

In order to secure the front and rear sections of the holder together, and in order 100 to provide a suitable support for the holder, each section is provided with a downwardly extending flange 18—19, and a clamp 20 is pivotally secured to one of the flanges and is formed with the spaced walls 21—22, 105 adapted when in closed position to embrace the flanges 18—19 therebetween and thus hold the sections in assembled position.

In order that the clamp may be easily moved into its locked position or displaced 110

therefrom, the rear wall 21 is preferably provided with the thumb projection 26, thus rendering the removal or insertion of the watch conveniently possible.

5 The flanges and clamp are preferably so shaped as to rest flat upon a supporting surface, such as the top of a desk, and in order to maintain the watch in an upright though slightly inclined position, a rearwardly extending leg 23 is provided which is hingedly secured at its upper extremity 24 to the rear section of the watch holder and is provided with the protruding lug 25 which limits the hinged movement thereof. Thus 10 when the holder is not in use or whenever desired the leg 23 may be closed against the rear section of the holder.

15 The somewhat modified form of holder illustrated in Figures 5 to 8 inclusive is designed and arranged for permanent securement to a supporting surface, such as the dashboard of an automobile, and to this end the front and rear sections 10'-11' are provided with the outwardly extending annular flanges 18'-19', suitable clamps 20' being hinged to one end of the flanges and are composed of the spaced walls 21'-22'. The clamps are also provided with the thumb projections 26', whereby they may be 20 conveniently operated. In this connection, it is to be noted that the rear spaced wall 22' of the clamp is of such length that when the clamp is rotated to its outer position, as illustrated in Figure 6, the rear wall is moved beyond the flange 19 of the watch 25 holder and thus releases the two sections and allows them to be moved apart.

20 The flange 19 of the rear section is provided with the openings 30 extending therethrough and adapted to receive the holding screws or fastening members 31. The flange 18' of the front section is provided with corresponding openings 32, somewhat larger, however, than the openings 30, so as to receive the heads 33 of the fastening members therethrough; whereby the fastening members 31 do not in any way interfere with the assembling or removal of the front section, the clamps 20' alone holding the sections together.

25 In some instances it has been found desirable to positively lock the front and rear sections of a watch holder together and thus prevent the theft of the watch, and to this end I have provided the rear section with additional openings 34, more clearly illus-

trated in Figure 8, and the flange of the front section with the non-circular holes or openings 35. A holding bolt 36 extends through the support 37, through the opening 34 in the flange of the rear section, and is provided with a non-circular head 38 which, when aligning with the non-circular opening 35 of the front flange, is adapted to pass therethrough. A suitable nut or 60 nuts 39 are adapted to hold the bolt in place and prevent its rotation. With the parts as thus constructed, when it is desired to remove the watch from the holder, the nuts 39 are first loosened, allowing the head 38 65 to be rotated into alignment with the opening 35 of the front flange, allowing the front section to be removed after the clamps 20' have been rotated or turned into their 70 unlocked position. After a new watch has been inserted in the holder and the front section replaced, the holding bolt is again rotated, causing the head to positively engage the flange of the front section and thus lock the sections together, so that with the 75 nuts 39 tightened in place it will be practically impossible for the watch to be stolen from the holder.

Having thus described and explained my invention, I claim and desire to secure by Letters Patent:

8 A watch holder comprising front and rear sections having adjacent parts shaped to form a watch-receiving receptacle, said front and rear sections provided with outwardly extending flanges, a clamp pivotally engaging one of the flanges and adapted to rotate into engagement with the other of the flanges and hold the two locked together, the flange of the rear section provided with 90 openings extending therethrough, holding bolts extending through said openings, and the flange of the front section provided with openings adapted to align with the openings of the rear section, with several of the 95 openings of the front section of non-circular outline and adapted to be engaged by the head of the holding bolts which extend therethrough.

100 Signed at New York, borough of Manhattan, in the county of New York and State of New York, this 27th day of January, A. D. 1921.

105 ALEXANDER MILNE.
